WASHING MACHINE CYLINDER

Frank H. Smith, Summit, N. J., assignor to Elevator Supplies Company, Incorporated, Hoboken, N. J., a corporation of New Jersey

Application March 24, 1932. Serial No. 600,859

2 Claims. (Cl. 68—18)

This invention relates to the cylinders or shells of washing machines, and particularly to the door-closures thereof, and provides improvements therein.

5 In the operation of washing machines, during the time the rotary cylinder or basket is turning, especially when turning upwardly with respect to the door, the washing solution is entrained by the cylinder and forced against the door where it meets the sill or ledge of the opening in the shell and often causes a spillage or leakage between the bottom of the door and the ledge, causing a wetness and unsanitary condition where the workers stand in loading and unloading the machine.

10 The present invention provides a door arrangement whereby the forcing of the washing solution between the ledge and the bottom of the closed door, by the action of the rotating cylinder or basket, and leakage and an unsanitary condition in front of the machine prevented. The invention further provides a simple, durable and effective means for its purpose.

15 An embodiment of the invention is illustrated in the accompanying drawing, wherein:

Figure 1 is a cross-section through a washing machine in the vicinity of the door; and

Fig. 2 is a perspective view of a ledge forming part of the invention.

20 Referring to said drawing, numeral 10 designates the rotary cylinder or basket, usually with a perforated cylindrical wall 12, and having inwardly extending hollow ribs 14 which act to pound and tumble the wash. The dot-and-dash line 15 indicates the approximate solution-level therein. Numeral 20 designates the shell or cylinder, which contains the washing solution, and in which the cylinder or basket 10 is rotatably mounted in the usual or any desired manner. Numeral 22 designates a door adapted to close the opening 24 through which the wash is put into and removed from the cylinder or basket 10. A handle 23 may be provided by which to grasp the door in moving it. The door 22 is preferably a sliding door, being retained and guided in its sliding movement by strips 25 forming grooved ways 26 at the sides of the door. A slot 28, closed by a cover 29, may be provided in door 22 for looking into the machine while the door is closed.

25 Numeral 30 designates a ledge running along the edge of the shell 20 at the bottom of the opening 24, and against which the lower edge of the door is adapted to rest in closed position, and constituting a sill therefor. The ledge 30 is

provided with a portion 32 projecting inwardly into cylinder 20 and acting as a deflector for washing solution entrained by and driven upwardly against the ledge by the rotating cylinder or basket 10. The impact of the hollow ribs 14 on the entrained washing solution as the ribs pass the sill is probably an important factor in causing leakage between the lower edge of the door and the sill in machines not provided with the present improvements. The 60 ledge 30 is preferably counter-sunk below the portion 32, as indicated at 34 to receive the upper edge portion 36 of the shell 20, the ledge and edge portion being fastened together by rivets or the like, as shown.

65 The ledge 30 is also provided with a shoulder 37 on which the bottom of the door 22 may rest, and is preferably sloped downwardly from the shoulder 36 to the tip of the projecting portion 32, as indicated at 38, to deflect inwardly water 70 running down the inner side of the door 22 from above. Behind the lower edge of the door 22 in its closed position there is arranged a flange 40, which may be and preferably is formed as an upward projection from the ledge 75 30, and which laps the lower rear edge of the door 22 and which provides a head behind the lower edge of the door above which the washing solution must rise before it can escape and leak. 80 This flange or portion 40 together with the deflecting projection 32 forms an effective stop against washing solution driven toward the meeting surfaces of the lower edge of the door 22 and the shoulder 37 of the ledge, being expelled from the machine.

85 Numeral 44 designates a loading shelf customarily used in washing machines, pivotally mounted in brackets 46.

90 Washing solution entrained by the cylinder or basket 10, as heretofore described, is deflected inwardly away from the sill 30 and constrained from flowing beyond said projection 32; and the washing solution driven under the impact of the hollow ribs 14 is likewise deflected and constrained by said inwardly projecting portion 32; and, as heretofore stated, the head afforded by the flange 40 at the rear of the door 22 in its closed position in conjunction with the portion 32 effectively overcomes 95 the forces tending to expell washing solution 100 from the machine.

105 The invention may have other forms within the scope of the claims than that herein specifically illustrated and described.

110 What is claimed is:—

1. A washing machine comprising a rotary basket and a cylinder enveloping the same adapted to contain a washing solution, said cylinder having an opening in its arcuate portion above the solution level, a door adapted to close said opening, a ledge along the bottom of said opening and a fixed projection in the cylinder adjacent the bottom of said opening of less length than the distance between the cylinder and basket having an inclined surface to deflect inwardly streams of solution entrained by the rotation of the basket.

2. A washing machine comprising a rotary basket and a cylinder enveloping the same adapted to contain a washing solution, said cyl-

inder having an opening in its arcuate portion above the solution level, a sliding door adapted to close said opening, and a ledge along the bottom of said opening having a sill on which the bottom of said door rests in closed position and a fixed projection in the cylinder adjacent the bottom of said opening, of less length than the distance between the cylinder and basket, having an inclined surface to deflect inwardly streams of solution entrained by the rotation of the basket, and a flange on the ledge extending upwardly from the bottom of said opening and engaging the outside of the lower part of said door in its closed position.
